UNITED STATES PATENT OFFICE.

JOHN H. HOMRIGHOUS, OF OAK PARK, ILLINOIS, ASSIGNOR TO AUTOMATIC ELECTRIC COMPANY, OF CHICAGO, ILLINOIS, A CORPORATION OF ILLINOIS.

VOICE-CURRENT TELEPHONE REPEATER.

Application filed March 27, 1919. Serial No. 285,586.

To all whom it may concern:

Be it known that I, JOHN H. HOMRIGHOUS, a citizen of the United States of America, and resident of Oak Park, in the county of Cook and State of Illinois, have invented certain new and useful Improvements in Voice-Current Telephone Repeaters, of which the following is a specification.

My invention relates in general to voice current repeaters for use in telephone systems, and more specifically to the amplification and transmission of voice currents in both directions. Among the features of my invention is to provide in such a system a repeater circuit, which is normally in full repeating relation in both directions, that is, it does not require a voice controlled switch for putting into communication the two terminating telephone stations, further features are the provision of voice operated circuit changing means so as to prevent the so called "singing" of the repeater system, by controlling the circuits of the system in such a manner that the amplifying device in the end opposite to that of the receiving end is inoperative during speech transmission. A further object of the system described herein is the provision of a special form of alternating current relay for use in the repeater circuit.

Repeaters for accomplishing certain of the above results have been used, but so far none have been designed which, while in normally full repeating relations in both directions will automatically adjust itself with reference to the desired direction of speech transmission, without a complicated arrangement of circuits and devices being used or without a large loss of energy. It is thought that the following description of my improved repeater will make clear to one skilled in the art that these results have been accomplished by the arrangement shown in the drawings in a very highly desirable form in which the transmission loss is practically negligible. Having pointed out the features of my invention and the general method of accomplishing the desired results, I will now describe the operation in detail by referring to the accompanying drawings.

In the drawings Fig. 1 represents the form of circuit arrangement for carrying out my invention.

Figures 2 and 3 represent details of the special type of relay used in the repeater system.

Referring first to Figs. 2 and 3, the reference character 4 represents a permanent magnet secured to a base plate 5 of non magnetic material. Secured at the ends of the magnet 4 and extending upward are the core pieces 14 and 15 for the coils 16. Above the core pieces 14 and 15 a narrow strip of flexible material 17 which forms the armature for the relay is suspended between the upper extremities of a U shaped member 18, which member is rigidly secured to the base plate 5 by means of screws, best shown in Fig. 3. Projecting downward from the lever 19 is a stem 20 which passes through an opening in the armature 17 and is firmly secured thereto by nuts. One end of the lever 19 is pivoted to the member 21; the opposite end is provided with a contact which in normal position rests between the contacts on springs 7 and 10. The springs 7 to 10 inclusive, are secured to the member 6 which is firmly fastened to the base plate 5. Near the end of member 6 a portion 11 is formed into a U shaped structure so that the screw 13 in the lower end passes through an opening in spring 10 and rest against the heavy spring 9. Likewise the screw 12 passes through an opening in the spring 7 and rest against the heavy spring 8. The light springs 7 and 10 are tensioned to follow the heavy springs 8 and 9 respectively, so that by means of the adjusting screws 12 and 13 the contacts on the springs 7 and 10 may be brought as close to the contact on the lever 19 as desirable. The operation is as follows: When the armature 17 is caused to vibrate by alternating or undulating current flowing through the coils 16, the lever 19 will vibrate and make contact with the springs 7 and 10. The springs 7 and 10 will follow the lever 19, that is, the lever 19 will contact with spring 7 before spring 10 breaks contact, and vice versa. By connecting the springs 7 and 10 together, a circuit may be closed by the lever 19 contacting either spring, that is, when the armature 17 is flexed in either direction responsive to the first alternation of current in the coils 16 one of the springs will be contacted. Therefore, it will be seen that I have devised a very efficient sensitive alternating current relay which is adapted for

many uses, and which may be arranged to operate with voice current.

Referring now to Figure 1 of the drawings, E and F represent the ends of toll lines between which is inserted the two-way repeating apparatus. 30 and 31 represent diagrammatically one way repeaters. Repeater 30 is arranged for repeating voice currents traveling in the direction from F to E and repeater 31 is arranged for repeating voice currents traveling in the direction from E to F. Repeaters 30 and 31 may be any repeater known in the art, but are herein represented as repeaters of ordinary construction consisting in each case of an electromagnet operating a microphone. Line E is inductively connected through primary winding 32 and secondary winding 35 of the receiving circuit of repeater 31, to the electromagnet of repeater 31 in bridge with the sensitive relay 37'. The transmitting circuit of the same repeater is inductively connected to the line F through primary winding 38 and secondary winding 37. Line F is connected through winding 37 in series with primary winding 36 which winding is inductively connected through secondary winding 39 of a transformer to the energizing portion of repeater 30 in bridge with the sensitive relay 38'. The transmitting circuit or reinforcing portion of repeater 30 is inductively connected through primary winding 34 and secondary winding 33 to the line E. The sensitive relays 37' and 38' are preferably of the type hereinbefore described in connection with Figures 2 and 3. Relay 37', which is operated by the voice currents induced in the receiving circuit of repeater 31 via line E controls a second relay 39' which relay 39' is normally partially energized by means of its lower winding so that it will operate its armature quickly when the circuit for its upper winding is closed. Springs 41 controlled by relay 39' are arranged to short circuit the electromagnet of repeater 30 and the sensitive relay 38'. Likewise, the sensitive relay 38' controls a relay 40' similar to the relay 39', which relay 40' is adapted to short circuit the electromagnet of repeater 31 and the relay 37'.

The operation of the system described above is as follows: When comparatively weak or attenuated voice currents reach the two-way repeater circuit via line E, the electromagnet of repeater 31 and the sensitive relay 37' will be energized in multiple through primary winding 32 and secondary winding 35 of the receiving circuit associated with line E. The flow of voice current through the windings of relay 37' causes its armature to vibrate in a manner hereinbefore described to close a circuit for the upper winding of relay 39'. Relay 39' will now energize as the two windings assist each other, to short circuit at springs 41,

the electromagnet of repeater 30 and the relay 38' in the receiving circuit associated with line F, and renders the repeater 30 inoperative so as to prevent the so called "singing" of the repeater circuit. The electromagnet of repeater 31 which is energized in multiple with relay 37', will agitate its microphone in a manner well known in the art, to set up variation of current strength in the local circuit consisting of battery B' and primary winding 38. The current changes produced in the winding 38 cause a current of increased voltage to be induced in the winding 37. Therefore amplified voice currents will flow over line F.

The operation of the two-way repeater circuit for voice currents reaching it via line connection F will be similar to the operation just described, since the two-way repeater circuit shown is a symmetrical arrangement.

The springs 43 controlled by the relay 39' are adapted to control a normally open transmitting circuit of repeater 31, that is, the circuit consisting of battery B' and winding 38 would be closed at springs 43 upon the operation of relay 39'. Likewise the springs 44 may control a normally open transmitting circuit of repeater 30.

It will be seen therefore, that I have provided a very simple and highly desirable type of voice current repeater in which the two terminating stations are normally in full repeating relation in either direction.

Having fully described and ascertained the features of my invention and method of accomplishing the desired results, I will point out in the appended claims what I consider to be new and desire to have protected by Letters Patent.

What I claim as my invention is:

1. In a telephone system, a pair of lines joined by a two-way repeating apparatus, said apparatus consisting of two repeaters each normally in full repeating relation to one of said lines, and a voice current controlled circuit changing device included in the energizing circuit of each repeater and operating with its associated repeater to render the other repeater inoperative.

2. In a telephone system, a pair of lines joined by a two-way repeating apparatus, said apparatus consisting of two repeaters each normally in full repeating relation to one of said lines, an energizing circuit for each repeater, a voice current controlled circuit changing device electrically connected in multiple with the energizing circuit of each repeater, and circuits whereby the device in the circuit of one repeater renders the other repeater inoperative while said first repeater is operating to repeat voice currents.

3. In a telephone system, a pair of lines joined by a two-way repeating apparatus,

- 10 said apparatus consisting of two repeaters each normally in full repeating relation to one of said lines, an energizing circuit for each repeater, a voice current controlled circuit changing device in the energizing circuit of each repeater, and means whereby the device in the energizing circuit of one repeater renders the other repeater inoperative while said first repeater is operating to repeat voice currents.
- 15 4. In a telephone system, a pair of lines joined by a two-way repeating apparatus, said apparatus consisting of two repeaters each normally in full repeating relation to one of said lines, an energizing circuit for each repeater, a voice actuated circuit controlling device in the energizing circuit of each repeater, and means whereby each device renders a different one of said repeaters inoperative while the other repeater is operating to repeat voice currents.
- 20 5. In a telephone system, a pair of lines joined by a two-way repeating apparatus, said apparatus consisting of two repeaters each normally in full repeating relation to one of said lines, an energizing circuit for each repeater, a voice current controlled circuit changing device in the energizing circuit of each repeater, and means whereby the device in the energizing circuit of one repeater renders the other repeater and its associated device inoperative while said first repeater is operating to repeat voice currents.
- 25 6. In a telephone system, a pair of lines joined by a two-way repeating apparatus, said apparatus consisting of two repeaters each normally in full repeating relation to one of said lines, an energizing circuit for each repeater, a voice current controlled circuit changing device in the energizing circuit of each repeater, and circuit connections whereby the device in the energizing circuit of one repeater short-circuits the energizing circuit of the other repeater while said first repeater is operating to repeat voice currents.
- 30 7. In a telephone system, a pair of lines joined by a two-way repeating apparatus, said apparatus consisting of two repeaters each normally in full repeating relation to one of said lines, an energizing circuit for each repeater, a voice current controlled device in the energizing circuit of each repeater, and circuit changing means controlled by said devices arranged to render the energizing circuit of a respective one of said repeaters inoperative.
- 35 8. In a telephone system, a pair of lines joined by a two-way repeating apparatus, said apparatus consisting of two repeaters each normally in full repeating relation to one of said lines, an energizing circuit for each repeater, a voice current controlled device in the energizing circuit of each repeater, and a voice current repeater always
- 36 9. In a telephone system, a pair of lines joined by a two-way repeating apparatus, 70 said apparatus consisting of two repeaters each normally in full repeating relation to one of said lines, an energizing circuit for each repeater, a voice current controlled device in the energizing circuit of each repeater, and direct current relays controlled by said devices, each of said relays arranged to render one of said repeaters inoperative.
- 40 10. In a telephone system, a pair of lines joined by a two way repeating apparatus, 80 said apparatus consisting of two repeaters each normally in full repeating relation to one of said lines, an energizing circuit for each repeater, a sensitive relay in metallic relation to the energizing circuit of each repeater; and direct current relays controlled by said sensitive relays, each direct current relay arranged to render one of said repeaters inoperative.
- 45 11. In a telephone system, a pair of lines joined by a two way repeating apparatus, 90 said apparatus consisting of two repeaters each having an electromagnet and each normally in full repeating relation to one of said lines, a circuit for each of said electromagnets, a sensitive relay in multiple with the circuit of each electromagnet, and direct current relays controlled by said sensitive relays, said direct current relay arranged to render one of said repeaters inoperative 95 while said other repeater is operating to repeat voice currents.
- 50 12. In a telephone system, a pair of lines joined by a two-way repeating apparatus, 105 said apparatus consisting of two one-way repeaters each having an electromagnet and each normally in full repeating relation to one of said lines, a circuit for each of said electromagnets, a sensitive relay in the circuit of each electromagnet, and normally partially energized relays controlled by said sensitive relays, each one of said second relays arranged to render one of said repeaters inoperative while the other one of said repeaters is operating to repeat voice currents. 110
- 55 13. In a telephone system, a pair of lines joined by a two-way repeating apparatus, 115 said apparatus consisting of two one-way repeaters each having an electromagnet and each normally in full repeating relation to one of said lines, a circuit for each of each electromagnets, a sensitive relay in the circuit of one of said electromagnets, and a normally partially energized relay controlled by said sensitive relay and arranged to short 120 circuit the electromagnet of the other repeater while said first repeater is operating to repeat voice currents.
- 60 14. In a telephone system, a pair of lines joined by a voice current repeater always 125

- in full repeating relation to one of said lines, comprising an amplifier for repeating in each direction over said lines, and a voice current controlled switching device for each line connected directly to the energizing circuit of each of said amplifiers, each device controlled from its associated line to short circuit one of said amplifiers.
15. In a telephone system, a line, a transformer for said line, a second line, a transformer for said second line, an energizing circuit for each transformer, voice current controlled devices associated with each line and connected in multiple with the energizing circuit of each of said transformers, and circuits whereby each device short-circuits a winding of one of said transformers.
16. In a telephone system, a line, a transformer for said line, a second line, a transformer for said second line, an energizing circuit for each transformer, voice current controlled circuit changing devices associated with each line connected directly to the energizing circuit of each of said transformers, the devices associated with said first line and controlled thereover being arranged to short circuit a winding of the transformer of said second line.
17. In a telephone system, a pair of lines joined by a two-way repeating apparatus, said apparatus consisting of two repeaters each normally in full repeating relation to one of said lines, and a voice current controlled circuit changing device permanently included in the energizing circuit of each re-
- peater and operating with its associated repeater to render the other repeater inoperative.
18. In a telephone system, a pair of lines joined by a two-way repeating apparatus, 40 said apparatus consisting of two one-way repeaters each having an electromagnet and each normally in full repeating relation to one of said lines, a circuit for each of said electromagnets, a sensitive relay in the circuit of each one of said electromagnets, a relay having two windings, one of said windings permanently energized and the other controlled by one of said sensitive relays to cause said relay to short circuit the electromagnet of one repeater while the other repeater is operating to repeat voice currents, 45 and a similar double wound relay controlled by the other of said sensitive relays.
19. In a telephone system, a pair of lines 55 joined by a two-way repeating apparatus, said apparatus consisting of two repeaters each having a multiple circuit included therein comprising a transformer winding, and a plurality of relays, said relays all operable in response to a current induced in the transformer, one of said relays for operating an amplifying device to transmit amplified voice currents to one of said lines and the other relay operating to make the 60 amplifying device associated with the other line inoperative.

Signed by me at Chicago, Cook County, Illinois, this 25th day of March, 1919.

JOHN H. HOMRIGHOUS.
